CHOKELESS NECK ROPE FOR A HORSE

James D. McGrew, 8120 Rio Linda Blvd.,
Elverta, Calif. 95626

Filed Feb. 16, 1973, Ser. No. 333,050

Term of patent 14 years

Int. Cl. D30—04

U.S. Cl. D30—19

FIG. 1 is a front elevational view of a chokeless neck rope for a horse, showing my new design;

FIG. 2 is a left side elevational view thereof;

FIG. 3 is a rear elevational view;

FIG. 4 is an enlarged scale fragmentary view of the upper end of the chokeless neck rope for a horse, showing the eye curved toward the adjacent monkey fist; and,

FIG. 5 is an enlarged scale fragmentary view of the upper portion of the chokeless neck rope for a horse shown in an operative condition.

I claim:

The ornamental design for a chokeless neck rope for a horse, as shown and described.
